DAVID JULIAN, OF COLUMBUS, OHIO, ASSIGNOR TO THE E. J. MANVILLE MACHINE COMPANY, OF WATERBURY, CONNECTICUT, A CORPORATION OF CONNECTICUT.

MACHINE FOR FORMING NUT-BLANKS.

1,330,122.

Specification of Letters Patent.

Patented Feb. 10, 1920.

Application filed October 28, 1918. Serial No. 259,949.

To all whom it may concern:

Be it known that I, DAVID JULIAN, a citizen of the United States, residing at Columbus, in the county of Franklin and State 5 of Ohio, have invented a new and useful Improvement in Machines for Forming Nut-Blanks, of which the following is a specification.

This invention relates to those metal working machines which are designed to automatically form square, hexagonal or other shape nut-blanks of various sizes from a bar 10 or coil of stock by the cold process.

The object of the invention is to provide 15 a machine of this class with straightening, feeding, piercing and shaping mechanisms so constructed and coöperating that the stock will be accurately fed and surely pierced and shaped in such manner that the 20 nut-blanks may be produced with a minimum expenditure of power, very rapidly and without danger of breaking the tools or producing imperfect blanks.

The stock used in the machine illustrated 25 is a bar or coil of steel, brass, or other metal of rectangular cross-section and indefinite length. In this machine there are oscillatory jaws for gripping and feeding the stock, reciprocating and stationary crimping ribs for straightening the stock before it reaches the feed jaws, means for preventing 30 a retrograde movement of the stock after it has passed the feed jaws, means for gaging the feed of the stock, means for preventing 35 the feed of the stock out of correct time, a reciprocating punch and stationary die for piercing holes in the fed stock, a reciprocating punch and fixed die for cutting off and shaping the pierced stock,—the 40 piercing punch and the shaping punch being mounted on the same slide and the piercing die and shaping die being formed in a common block,—a die that coöperates with the shaping punch for chamfering the 45 sheared pieces, and a die that coöperates with the shaping punch for trimming the chamfered pieces,—the chamfering die and trimming die being mounted on a common vertically movable slide and presented alternately in axial alinement with the shaping 50 die.

Figure 1 of the accompanying drawings shows a plan of the front portion of the machine. Fig. 1^a shows a plan of the rear portion of the machine. Fig. 2 shows on

larger scale a vertical section through the feed mechanism on the plane indicated by the dotted line 2—2 on Fig. 1. Fig. 3 shows on a still larger scale a plan of the feed jaws and a part of the mechanisms provided 60 for rendering the feed-jaws inactive and for preventing the feed mechanism from being thrown into active operation out of time. Fig. 4 shows an enlarged vertical section of the means provided for adjusting the distance of movement of the feed-jaws, the section being taken on the plane indicated by the dotted line 4—4 on Fig. 1. Fig. 5 shows a plan of the oscillatory feed-arm which carries the gripping feed-jaws, illustrating the means for adjusting the tightness of the grip of the feed-jaws on the stock. Fig. 6 shows a plan of the feed-arm lever which is pivotally mounted on and adjustably connected with the feed-arm. Fig. 7 75 shows a vertical section of the machine on the plane indicated by the dotted line 7—7 on Fig. 1, which is the plane on which the plan views Fig. 1 and Fig. 1^a are separated.

Fig. 8 shows, on larger scale than in Fig. 80 7, a vertical section taken through the shaping-die, chamfering-die and trimming-die. Fig. 9 shows, on larger scale, a plan of the reciprocating piercing-punch and shaping-punch holder with the punches in place, and 85 a horizontal section through the shaping-die and trimming-die. Fig. 10 shows a face view of the die-block with the piercing-die and shaping-die, and the gage which is used to determine the initial position of the stock 90 and which is afterward employed for holding the stock down against a shoe underneath and centering it vertically.

The rectangular stock 1 is drawn into the machine between the vertical rolls 2 and 95 the horizontal rolls 3 and advanced to the straightening mechanism. The straightening mechanism has a plate 4 with three or more vertical crimping ribs 5, the ribbed-plate being set to the desired position by the 100 adjusting screws 6. Coöperating with the stationary ribbed-plate 4 is a plate 7 provided with two or more vertical crimping ribs 8. The plate 7 is mounted on a slide 9 that is movable back and forth horizontally 105 between guide plates 10 which are fastened to the frame. This slide is adjustably connected by a union nut 11 with an eccentric rod 12 that projects from an eccentric strap 13 which encircles an eccentric 14. This eccen- 110

tric is fastened to the main shaft 15 that is rotated by the driving pulley 16, Fig. 1. By the coöperation of the stationary crimping ribs and the crimping ribs which are reciprocated by the eccentric the stock is straightened before it passes to the feeding mechanism.

The feed jaws swing horizontally inward for advancing the stock toward the tools and outward for obtaining a fresh hold on the stock. The anvil-jaw 17 on one side occupies a positive position with relation to the stock, whereas the pinch-jaw 18 on the other side is movable toward and from the stock. Both jaws are carried by an oscillatory feed-arm 19 which is pivotally held on the frame by a stud 20, and which is oscillated by the movements of the feed-arm-lever 21. One end of this feed-arm-lever is pivoted by the stud 22 to the feed-arm, while the other end of the lever is, by a link 23, connected with a slide 24 which is jointed to an eccentric strap 25 that encircles an eccentric 26 on the main shaft, Fig. 1.

Extending upwardly from the feed-arm through an opening in the feed-arm-lever is a hub 27 the function of which is to transmit oscillatory movements of the feed-arm-lever to the feed-arm, and enable an easy and accurate adjustment of the amount of movement thus imparted. Movable located in horizontal slots in the top of this hub are two hardened blocks 28 and opposite these blocks in vertical slots in the feed-arm-lever are two hardened shoes 29, Figs. 4, 5, 6. Withdrawing these blocks into the hub diminishes the amount of movement imparted by the feed-arm-lever to the feed-arm as under this condition there is more lost motion between the blocks and shoes, and advancing the blocks from the hub increases the amount of movement imparted to the feed-arm, as by this action there is less lost motion between the blocks and shoes. For advancing or withdrawing these blocks their upper surfaces are provided with scroll threads 30, Figs. 4, 5, and these threads are engaged by scroll threads 31 on the underside of a thumb nut 32 which turns on a stud 33 which extends from the feed arm upwardly through the hub. The upper end of this stud is threaded and provided with a clamp-nut 34 that has a handle 35. When the clamp-nut is loosened the blocks may be adjusted in or out by turning the thumb-nut in the proper direction and when the clamp-nut is tightened the blocks are securely held, Fig. 4.

The anvil-jaw 17 is loosely mounted in a horizontal groove in the top of the swinging end of the feed-arm. Thrusting between the outer end of this jaw and a plate 36 that is adjustably connected with the end of the arm by screws 37 is a stiff spiral spring 38. This spring back of this jaw

regulates the gripping tension, allows for variations in the thickness of the stock, and yields in case of emergency. The tension of the spring is regulated by means of the adjusting screws 37 and stop screws 39, 70 and the amount of inward movement of the anvil-jaw under the thrust of the spring is limited by the engagement of the nuts 40 threaded on the jaw stem 41, with the outer face of the plate 36, Figs. 2, 3.

In the upper face of the anvil-jaw are transverse grooves 42 and 43 and movable through these grooves transversely of the jaw and lying in grooves 44 in the top of the end of the feed-arm are racks 45 and 46 80 which are engaged by a pinion 47.

On the rack 45 is a wedge 48 that is adapted to engage with an inclined surface 49 on the jaw. When the rack 45 is in the position shown in Fig. 3 the wedge is disengaged from the incline and consequently the spring can force the anvil-jaw inward against the stock, but when the rack is moved to its other position the wedge engages the incline and forces the anvil-jaw back against the pressure of the spring so that it will not pinch against the stock. These positions of the racks are controlled by the positions of the pins 50 and 51 which have a vertical movement in a part of the fixed frame, and are adapted to be raised and lowered by throwing the handle 52 to one side or the other. When the handle is in the position shown in Fig. 2 the pin 51 is forced down and projects into the slot 53 in the rack 46 so that on the retrograde swing of the arm with the rack, the pin will engage the end of the slot 53 and hold the rack 46 while the arm continues to swing. This causes the pinion to rotate and draw the rack 45 so the wedge 100 on that rack will be free from the incline on the jaw, as shown in Fig. 3, and leave the jaw free to be pressed by the spring against the stock. When the handle is thrown in the opposite direction the pin 51 110 is drawn up and the pin 50 pushed down into the slot 54 in the rack 45. This pin then, as the feed-arm swings back, engages the end of the slot 54 and holds the rack 45 so that the wedge it carries will engage the inclined surface and press the anvil-jaw back against the spring, and hold the jaw away from the stock. This construction permits the engaging or disengaging of the feed when the feed-arm is returning, which, of course, eliminates the possibility of feeding any length of stock less than that required to make a full blank, Fig. 3.

The pinch jaw 18 is loosely mounted in a groove in the upper surface of the feed arm 125 19 and is connected by a right and left threaded stud 60 with the front section 61 of a slide, Figs. 2, 5. The rear section 62 of this slide bears a roll 63 that is engaged by a cam 64 on the main shaft 15. The joint 130

65 between the slide sections is formed somewhat loose and in such manner that the slide sections may be reciprocated together while allowing the front section to swing with the 5 feed arm. A spring 66 is arranged between a pin 67 projecting from the front section and a pin 68 projecting from the frame to hold the joint between the slide sections tight and draw the slide back and hold the roll 10 against the cam, Fig. 2. This cam is so timed that it causes the pinch jaw to press the stock against the anvil-jaw during the time of feed and release the stock during the retrograde movement of the jaws.

15 In order to locate the stock when it is fed into the machine so that the first hole will be pierced in the correct position a stop-gage 69 is provided. This gage has a vertical movement in the die-block holder 70 and 20 is connected with an overhead lever 71 by means of which it may be raised and lowered, Fig. 10. When lowered it projects into the path of the stock so that the end of the stock will butt against it. This insures the 25 exact distance between the end of the stock and the piercing-hole 72 in the die-block 73. After the stock has been properly located the lever is turned by hand so as to raise the stop-gage and permit the stock to 30 feed. Subsequently the stop-gage is allowed to bear upon the top of the stock and hold it down against the stock-rest 74, the stop-gage and stock-rest being adjusted to centralize the stock with relation to the 35 piercing-punch and die and shaping-punch and die.

The stock passes into a channel 75 in a bracket 76 located on the top of the frame, and to prevent any retrograde movement of 40 the stock after it has been fed and when the feeding jaws are being returned, a clamping finger 77 is pivoted in a bracket 78 on the top of the frame, Fig. 1. The swinging end of this finger which projects into the channel 45 is cam-shaped so that it offers no resistance to the forward movement of the stock, but wedges and binds the stock against any tendency to move backward. A spring 79 thrusts against this finger in such manner 50 as to cause its swinging end to bear against the stock for this purpose.

In the particular machine illustrated the end of the stock is fed first in front of the piercing-punch 80 which comes up and 55 punches a hole. The piercing-punch then withdraws and the stock is fed again. After the second feed the piercing-punch forms another hole. In this machine the shaping-punch 81 does not act on the stock until the 60 time that the third hole is pierced. The piercing-punch and shaping-punch are clamped in openings in the top of a slide 82 which is movable horizontally back and forth in ways in the top of the machine, 65 Figs. 7, 9. At the rear end this slide has

a roller 83 engaging with which is a cam 84 on the main shaft 15. At the side of this cam is a cam 85 that engages a roll 86 on the upper end of a lever 87. This lever is connected with a rocker arm 88 which has 70 its free end joined by a link 89 with the slide. The cam 84 through the roll drives the punch-slide forward, and the cam 85 through the roll, lever, rocker-arm and link draws the punch-slide backward, Figs. 7, 1 75 and 1^a.

The die-block 73 is circular and besides the piercing-punch hole 72 has the shaping die-hole 90. This may be any desired shape, that shown in the drawing being hexagonal, 80 Fig. 10, as the shaping-punch is hexagonal for the purpose of forming a hexagonal nut-blank.

The shaping-punch does not shear the stock until the third hole is pierced by the 85 piercing-punch. Subsequently, of course, the shaping-punch operates each time that a hole is punched by the piercing-punch. When the shaping-punch comes up it cuts off and drives the pierced end of the stock 90 into the shaping-die, causing the stock to conform to the shape of the die.

Back of the shaping-die and having a vertical movement in line therewith is a slide 91. This slide is connected by a link 92 with a rocker arm 93 which has a rocker 94 that is connected with a link 95, Fig. 7, which is reciprocated by a cam 96 on the main shaft, Fig. 1^a. The slide 91 carries a 95 chamfering die 97 and a trimming die 98, 100 the former being above the latter.

The end of the shaping-punch is slightly in advance of the end of the piercing-punch, and after the shaping-punch shears the 105 blank and drives it through the shaping-die the cam 84 forces the shaping-punch far enough forward to drive the blank into the chamfering die so as to shape the face of the blank. Then the shaping-punch carrying the blank, withdraws a slight distance 110 and the vertical slide is lifted to bring the trimming die 98 into line with the shaping-die. After this movement the cam 84 drives the shaping-punch still farther forward so as to force the blank, which has been 115 chamfered, through the shaping-die and into the discharge quill 99, Figs. 7, 8, 9. The following nut blank pushes the blank previously formed out along the discharge quill.

With this machine the stock is fed by 120 oscillatory positively gripping feed-jaws which can be so quickly and closely adjusted that the exact desired amount of feed of the stock may be obtained, and furthermore with the mechanism shown the stock is perfectly 125 free, that is, it is not bound by the straightening mechanism, when it is being fed so that the feed is easy and sure, and yet at the same time the stock is straightened and can not be withdrawn out of position by the 130

retrograde movement of the feed-jaws or by the resiliency of the stock, which is usually in the form of a coil on a reel at one side of the machine.

5 With the oscillatory positive grip-feed there is no slip, insuring an absolute advance of the stock the required distance, and as this feed is accomplished with but little power, and as there can be no retrograde 10 movement of the stock the danger of breaking the tools or injuring any of the mechanisms when the machine is in operation, owing to misfeed, is practically eliminated.

The invention claimed is;

15 1. In a machine for forming nut-blanks the combination with the piercing and shaping punches and dies, of oscillatory jaws for feeding stock to the punches and dies, means for oscillating the feed jaws, mechanism for 20 straightening the stock, and means for relaxing the straightening mechanism when the jaws oscillate forward for feeding the stock.

25 2. In a machine for forming nut-blanks the combination with the piercing and shaping punches and dies, of oscillatory jaws for feeding stock to the punches and dies, means for oscillating the feed jaws, crimping mechanism for pinching and straightening 30 the stock, and means for relaxing the straightening mechanism when the jaws oscillate forward for feeding the stock.

35 3. In a machine for forming nut-blanks the combination with the piercing and shaping punches and dies, of oscillatory jaws for feeding stock to the punches and dies, means for oscillating the feed jaws, a fixed plate and a movable plate for straightening the stock, and mechanism for reciprocating 40 the movable straightening plate toward and from the fixed straightening plate.

45 4. In a machine for forming nut-blanks the combination with the piercing and shaping punches and dies, of oscillatory jaws for feeding stock to the punches and dies, means for oscillating the feed jaws, mechanism for straightening the stock, means for relaxing the straightening mechanism when the jaws oscillate forward for feeding 50 the stock, and means for preventing retrograde movement of the stock when the feeding jaws are moving backward and the straightening mechanism is relaxed.

55 5. In a machine for forming nut-blanks the combination with the piercing and shaping punches and dies, of oscillatory jaws for feeding stock to the punches and dies, means for oscillating the feed jaws, mechanism for straightening the stock, means for 60 relaxing the straightening mechanism when the jaws oscillate forward for feeding the stock, and means for gaging the position of the stock when first fed and subsequently centering the stock with relation to the 65 punches and dies.

6. In a machine for forming nut-blanks the combination with the piercing and shaping punches and dies, of oscillatory jaws for feeding stock to the punches and dies, means for oscillating the feed jaws, mechanism for straightening the stock, means for relaxing the straightening mechanism when the jaws oscillate forward for feeding the stock, means for gaging the position of the stock with relation to the punches and dies, and means for preventing retrograde movement of the stock when the feeding jaws are moving backward and the straightening mechanism is relaxed.

7. In a machine for forming nut-blanks the combination with the piercing and shaping punches and dies, of oscillatory jaws for feeding stock to the punches and dies, means for oscillating the feed jaws, mechanism for straightening the stock, means for relaxing the straightening mechanism when the jaws oscillate forward for feeding the stock, means for gaging the position of the stock when first fed and subsequently centering the stock with relation to the punches and dies, and means for preventing retrograde movement of the stock when the feeding jaws are moving backward and the straightening mechanism is relaxed.

8. In a machine for forming nut-blanks the combination with the piercing and shaping punches and dies, of oscillatory jaws for feeding stock to the punches and dies, means for oscillating the feed jaws, mechanism for straightening the stock, means for relaxing the straightening mechanism when the jaws oscillate forward for feeding the stock, manually operated means for gaging the position of the stock with relation to the punches and dies, and means for preventing retrograde movement of the stock when the feeding jaws are moving backward and the straightening mechanism is relaxed.

9. In a machine for forming nut blanks the combination with the piercing and shaping punches and dies of an oscillatory arm, an oscillatory feed arm lever mounted on the arm, mechanism for oscillating said feed arm lever, an anvil jaw adjustably mounted on said arm, a pinch jaw movably mounted on said arm and mechanism for reciprocating said pinch jaw on the arm.

10. In a machine for forming nut-blanks the combination with the piercing and shaping punches and dies, of an oscillatory yieldingly mounted anvil jaw, an oscillatory and reciprocatory pinch jaw, and mechanism for oscillating and opening and closing the jaws.

11. In a machine for forming nut-blanks the combination with the piercing and shaping punches and dies, of an oscillatory anvil jaw, an oscillatory and reciprocatory pinch jaw, mechanism for oscillating and opening and closing the jaws, and means for with-

drawing the anvil jaw from operative position.

12. In a machine for forming nut-blanks the combination with the piercing and shaping punches and dies of an oscillatory arm, an oscillatory feed arm lever mounted on the arm, mechanism for oscillating said feed arm lever, an anvil jaw adjustably mounted on said arm, a pinch jaw movably mounted on said arm, mechanism for reciprocating said pinch jaw on the arm, mechanism for straightening the stock, and means for relaxing the straightening mechanism when said feed arm is oscillated forward for feeding stock.

13. In a machine for forming nut-blanks the combination with the piercing and shaping punches and dies, of an oscillatory anvil jaw, an oscillatory and reciprocatory pinch jaw, mechanism for oscillating and opening and closing the jaws, mechanism for straightening the stock, means for relaxing the straightening mechanism when the jaws oscillate forward for feeding stock, and means for centering the fed stock.

14. In a machine for forming nut-blanks the combination with the piercing and shaping punches and dies, of an oscillatory anvil jaw, an oscillatory and reciprocatory pinch jaw, mechanism for oscillating and opening and closing the jaws, mechanism for straightening the stock, means for relaxing the straightening mechanism when the jaws oscillate forward for feeding stock, and means for preventing a retrograde movement of the stock when the feeding jaws are moving backward and the straightening mechanism is relaxed.

15. In a machine for forming nut-blanks the combination with the piercing and shaping punches and dies, of an oscillatory anvil jaw, an oscillatory and reciprocatory pinch jaw, mechanism for oscillating and opening and closing the jaws, mechanism for straightening the stock, means for relaxing the straightening mechanism when the jaws oscillate forward for feeding stock, means for preventing a retrograde movement of the stock when the feeding jaws are moving backward and the straightening mechanism is relaxed, and means for centering the fed stock.

16. In a machine for forming nut-blanks the combination with the piercing and shaping punches and dies, of an oscillatory anvil jaw, an oscillatory and reciprocatory pinch jaw, mechanism for oscillating and opening and closing the jaws, mechanism for straightening the stock, means for relaxing the straightening mechanism when the jaws oscillate forward for feeding stock, means for preventing a retrograde movement of the stock when the feeding jaws are moving backward and the straightening mechanism is relaxed, and manually operated

means for gaging the position of the stock and subsequently centering the stock with relation to the punches and dies.

17. In a machine for forming nut-blanks the combination with the piercing and shaping punches and dies, of oscillatory jaws for feeding the stock to the punches and dies, means for oscillating the feed jaws, a fixed plate with crimping ribs and a reciprocatory plate with crimping ribs for straightening the stock, and mechanism for reciprocating the movable crimping plate.

18. In a machine for forming nut-blanks the combination with the piercing and shaping punches and dies, of oscillatory jaws for feeding the stock to the punches and dies, means for oscillating the feed jaws, a fixed plate with crimping ribs and a reciprocatory plate with crimping ribs for straightening the stock, mechanism for reciprocating the movable crimping plate, and means for preventing the retrograde movement of the fed stock.

19. In a machine for forming nut-blanks the combination with the piercing and shaping punches and dies, of oscillatory jaws for feeding the stock to the punches and dies, means for oscillating the feed jaws, a fixed plate with crimping ribs and a reciprocatory plate with crimping ribs for straightening the stock, mechanism for reciprocating the movable crimping plate, means for gaging the position of the stock with relation to the punches and dies, and means for preventing the retrograde movement of the fed stock.

20. In a machine for forming nut-blanks the combination with the piercing and shaping punches and dies, of mechanism for feeding the stock to the punches and dies consisting of an oscillatory feed arm, a feed arm lever pivotally mounted on said feed arm, means for oscillating the feed arm lever, a pair of feed jaws mounted on and swinging with said arm, one of said jaws being fixed with relation to the arm and the other being movable toward and from the fixed jaw, and means for reciprocating the movable jaw.

21. In a machine for forming nut-blanks the combination with the piercing and shaping punches and dies, of mechanism for feeding the stock to the punches and dies consisting of an oscillatory feed arm, means for oscillating the feed arm, a pair of feed jaws mounted on and swinging with said arm, one of said jaws being yieldingly mounted on said arm, a spring on said arm back of said jaw, means for adjusting said spring, and the other jaw being movable on said arm toward and from said yielding jaw, and means for reciprocating the movable jaw.

22. In a machine for forming nut-blanks the combination with the piercing and shap-

ing punches and dies, of an oscillatory feed arm, a feed arm lever pivoted on the feed arm, an adjustable connection between the feed arm and feed arm lever, means for oscillating the feed arm lever and swinging the feed arm, a pair of feed jaws mounted on the feed arm, and mechanism for opening and closing the jaws.

23. In a machine for forming nut-blanks 10 the combination with the piercing and shaping punches and dies, of an oscillatory feed arm, a feed arm lever pivoted on the feed arm, an adjustable connection between the feed arm and feed arm lever, means for oscillating the feed arm lever and swinging the feed arm, a pair of feed jaws adjustably mounted on the feed arm, and mechanism for opening and closing the jaws.

24. In a machine for forming nut-blanks 20 the combination with the piercing and shaping punches and dies, of an oscillatory feed arm, a feed arm lever pivoted on the feed arm, an adjustable connection between the feed arm and feed arm lever, means for oscillating the feed arm lever and swinging the feed arm, a pair of feed jaws mounted on the feed arm, and mechanism for reciprocating one jaw toward the other jaw.

25. In a machine for forming nut-blanks 30 the combination with the piercing and shaping punches and dies, of an oscillatory feed arm, a feed arm lever pivotally mounted on the feed arm, mechanism for oscillating the feed arm lever, adjustable means for connecting the feed arm lever with the feed arm, a pair of jaws mounted on the feed arm, one of said jaws being fixed with relation thereto and the other of said jaws being movable toward and from the fixed jaw, 40 and mechanism for reciprocating the movable jaw toward and from the fixed jaw, a part of said reciprocating mechanism oscillating with the feed arm.

26. In a machine for forming nut-blanks 45 the combination with the piercing and shaping punches and dies, of an oscillatory feed arm, a feed arm lever pivotally mounted on the feed arm, mechanism for oscillating the feed arm lever, adjustable means for connecting the feed arm lever with the feed arm, a pair of jaws mounted on the feed arm, one of said jaws being yieldingly fixed with relation thereto and the other of said jaws being movable toward and from the 55 relatively fixed jaw, and mechanism for reciprocating the movable jaw toward and from the fixed jaw, a part of said reciprocating mechanism oscillating with the feed arm.

27. In a machine for forming nut-blanks 60 the combination with the piercing and shaping punches and dies, of an oscillatory feed arm, a feed arm lever pivotally mounted on the feed arm, mechanism for oscillating the 65 feed arm lever, adjustable means for con-

nnecting the feed arm lever with the feed arm, a pair of jaws mounted on the feed arm, one of said jaws being fixed with relation thereto and the other of said jaws being movable toward and from the fixed jaw, 70 mechanism for reciprocating the movable jaw toward and from the fixed jaw, a part of said reciprocating mechanism oscillating with the feed arm, and means for withdrawing the relatively fixed jaw from active 75 position.

28. In a machine for forming nut-blanks 80 the combination with the piercing and shaping punches and dies, of a feed mechanism comprising an oscillatory feed arm, a feed arm lever pivotally mounted upon the feed arm, mechanism for oscillating the feed arm lever, jaws mounted upon the feed arm, mechanism for opening and closing the jaws, blocks having scroll teeth carried by 85 the feed arm and adapted to be engaged by the feed arm lever, and a nut carried by the feed arm and having scroll teeth meshing with the teeth of said blocks whereby the blocks may be adjusted for determining the 90 time of connection between the feed arm lever and feed arm.

29. In a machine for forming nut-blanks 95 the combination with the piercing and shaping punches and dies, of a feed mechanism comprising an oscillatory feed arm, a feed arm lever pivotally mounted upon the feed arm, mechanism for oscillating the feed arm lever, jaws mounted upon the feed arm, mechanism for opening and closing the 100 jaws, a hub extending from the feed arm through the feed arm lever, blocks having scroll teeth mounted in said hub and adapted to engage with the feed arm lever, and a nut carried by the feed arm and having scroll teeth meshing with the teeth of 105 said blocks whereby the blocks may be adjusted for determining the time of connection between the feed arm lever and feed arm.

30. In a machine for forming nut-blanks 110 the combination with the piercing and shaping punches and dies, of a feed mechanism comprising an oscillatory feed arm, a feed arm lever pivotally mounted upon the feed 115 arm, mechanism for oscillating the feed arm lever, jaws mounted upon the feed arm, mechanism for opening and closing the jaws, a hub extending from the feed arm through the feed arm lever, blocks having scroll teeth mounted in said hub and adapted to engage with the feed arm lever, a stud carried by the feed arm and extending through the hub, and a nut turning on 120 said stud and having scroll teeth meshing with the teeth of said blocks whereby the blocks may be adjusted for determining the time of connection between the feed arm lever and feed arm.

31. In a machine for forming nut-blanks 125

the combination with the piercing and shaping punches and dies, of feeding jaws, mechanism for oscillating the jaws, mechanism for opening and closing the jaws, 5 means for preventing the jaws from closing on and feeding the stock, and mechanism for throwing said means in and out of action, operable only on the returning swing of the feed jaws.

10 32. In a machine for forming nut-blanks the combination with the piercing and shap-

ing punches and dies, of feeding jaws, mechanism for oscillating the jaws, mechanism for opening and closing the jaws, means for preventing the jaws from closing 15 on and feeding the stock, and manually set mechanism for throwing said means in and out of action, which operates automatically only on the returning swing of the feed jaws.

DAVID JULIAN.
